VARIABLE TEMPERATURE REFRIGERATION

Carlyle S. Herrick, Alplaus, N. Y., assignor to General Electric Company, a corporation of New York

Application June 29, 1954, Serial No. 440,024

6 Claims. (Cl. 62—115)

This invention relates to refrigeration systems and specifically to a method and apparatus to secure variable temperature levels in such systems.

Variable temperature refrigeration systems are desirable in heat pump construction and in domestic and commercial refrigerators. It is desirable that a reverse refrigeration system or heat pump employ a refrigerant mixture whose composition is varied automatically to maintain a constant system capacity over a wide variation in evaporator temperatures. A single refrigerant system will not operate at constant capacity over such temperature variations.

Accordingly, it is an object of my invention to provide a new and improved refrigeration system in which a pair of partly miscible refrigerants are employed.

It is another object of my invention to provide a refrigeration system which circulates selectively a variable composition of refrigerants in response to the load upon the system.

It is another object of the invention to provide a refrigeration system in which the storage liquid receiver is maintained at condenser pressure.

It is another object of the invention to provide a refrigeration system in which the composition of the refrigerant mixture is determined by the evaporator temperature.

It is a further object of the invention to provide a novel method of refrigeration in which the composition of the refrigerant mixture in the refrigeration system is automatically varied to produce different temperature levels of refrigeration.

In carrying out my invention in one form, the composition of the refrigerant mixture is varied with the evaporator temperature to maintain a constant capacity refrigeration system.

These and various other objects, features and advantages of the invention will be better understood from the following description taken in connection with the accompanying drawing in which:

Fig. 1 is a schematic view of one form of a refrigeration system which embodies my invention; and

Fig. 2 is a schematic view of a second form of a refrigeration system.

In Fig. 1 of the drawing, a variable temperature refrigeration system which is indicated generally at 10, comprises a compressor 11 which communicates on its high pressure side with a condenser 12. Condenser 12 is connected to a liquid running receiver 13 in which a pair of partly miscible refrigerants are in a mixture 14 to circulate through the refrigeration system. An outlet 15 circulates mixture 14 through an expansion valve 16 to a heat exchange coil 17 within a liquid storage receiver 18. Coil 17 is connected to an outlet 19 in communication with the inlet side of an evaporator 20. Coil 17 is positioned in receiver 18 to cool the receiver to evaporator temperature. Expansion valve 16 is shown to be of a conventional type which is operated by a pressure tube 21 and diaphragm 22. A temperature-

2

operated or thermostatic valve or sections of capillary tubing could be employed as the expansion device. Evaporator 20 communicates with the inlet or low pressure side of compressor 11.

The storage receiver 18 is filled completely with an additional supply of the same refrigerants in two separate partly miscible phases or layers 23 and 24. Each of phases 23 and 24 contain both refrigerants in different proportions. Both receivers 13 and 18 are maintained at condenser pressure. Receiver 18 is connected to receiver 13 through a tube 25. A capillary tube 26 connects receiver 18 to outlet 15 between receiver 13 and expansion valve 16 to circulate slowly a continuous stream of refrigerant phase 23 thereto under gravity head. Tube 15 will replenish the refrigerants in receiver 18 from refrigerant mixture 14 in receiver 13. The temperature in receiver 18 is determined by coil 17 therein while the pressure is regulated by condenser 12.

The pair of refrigerants, which are employed in the refrigeration system, may be miscible at condenser temperature but must be only partly immiscible at customary evaporator temperatures. The pair of partly miscible refrigerants forms two separate phases in which each phase is rich in one of the refrigerants and contains also a substantial amount of the second refrigerant. The amount of the second refrigerant in each phase is controlled by the temperature. It is desirable to have a wide variation of phase composition with temperature in the customary evaporator temperature range. The two phases must also have different densities so that separation is possible by gravity. The pair of refrigerants must have different volatilities so that the refrigerating capacities of the system may be altered.

The following pairs of refrigerants are given as examples of suitable refrigerant mixtures to be employed in such a variable temperature system: ammonia (NH₃) and "Freon 12" (CF₂Cl₂), ammonia (NH₃) and "Freon 114" (C₂F₄Cl₂), ammonia (NH₃) and perfluorocyclobutane (C₄F₈), ammonia (NH₃) and "Freon 115" (C₂F₅Cl), ammonia (NH₃) and perfluoropropane (C₃F₈), sulfur dioxide (SO₂) and perfluorocyclobutane (C₄F₈), methylbromide (CH₃Br) and perfluorocyclobutane (C₄F₈), methylene chloride (CH₂Cl₂) and perfluoropropane (C₃F₈), ethylchloride (C₂H₅Cl) and perfluoropropane (C₃F₈), perfluoropropane (C₃F₈) and methylbromide (C₃F₈Br), perfluoropropane (C₃F₈) and methylchloride (CH₃Cl), perfluoropropane (C₃F₈) and "Freon 21" (CHFCl₂), perfluoropropane (C₃F₈) and "Freon 31" (CH₂FCl), perfluorobutane (C₄F₁₀) and "Freon 21" (CHFCl₂), perfluorobutane (C₄F₁₀) and methylene chloride (CH₃Cl), perfluorobutane (C₄F₁₀) and methylene chloride (CH₂Cl₂), perfluorobutane (C₄F₁₀) and ethylchloride (C₂H₅Cl), "Freon 115" (C₂F₅Cl) and methylene chloride (CH₂Cl₂), and "Freon 115" (C₂F₅Cl) and sulfur dioxide (SO₂).

In the operation of the refrigeration system which is shown in Fig. 1 of the drawing, compressor 11 pumps refrigerant mixture 14 through the condenser 12 to liquid running receiver 13. Refrigerant mixture 14 which may be miscible at condenser temperature is then circulated through outlet 15, expansion valve 16, coil 17, outlet 19, and evaporator 20 to the inlet side of compressor 11. Storage receiver 18, in which an additional supply of mixture 14 is contained in two separate partly miscible phases 23 and 24, is connected to both receiver 13 and outlet 15. Capillary tube 26 from receiver 18 provides a slow, continuous circulation of phase 23 to outlet 15 to vary the composition of refrigerant mixture 14 in response to the system load. Refrigerant phase 23 is shown to be the operating phase while the phase 24 is the storage phase. An increase in the evaporator temperature increases the concentration of the low capacity refrigerant in phase 23

while a decrease in evaporator temperature increases the concentration of the high capacity refrigerant in phase 23. Thus, the capacity of the refrigeration system remains automatically constant over a wide range of temperature variations.

Refrigerant mixture 14 is withdrawn from receiver 13 through tube 25 to replenish the refrigerants in receiver 18 which are circulated to the system from phase 23 thereof. The composition of refrigerant mixture 14 is determined by the system load through the pressure variations of the evaporator. However, the volume of the refrigerant mixture remains constant in the refrigeration system through the addition of refrigerant phase 23 and the corresponding withdrawal of circulating mixture 14.

In Fig. 2 of the drawing, a modified refrigeration system is shown in which the cooling coil section 17 in Fig. 1 is eliminated. Storage receiver 18 is positioned in the refrigeration system adjacent evaporator 20 or the outdoor air to cool the refrigerants therein to evaporator temperature to provide separation into two separate partly miscible phases or layers 23 and 24. Liquid running receiver 13 is connected directly to evaporator 20 through outlet 15 with expansion valve 16 therein. The refrigeration system of Fig. 2 is otherwise similar in structure and operation to the refrigeration system which is disclosed in Fig. 1.

As will be apparent to those skilled in the art, the objects of my invention are attained by the use of a refrigerant mixture which is varied with the evaporator temperature to maintain a constant capacity refrigeration system.

While other modifications of this invention and variations of apparatus which may be employed in the scope of the invention have not been described, the invention is intended to include all such as may be embraced within the following claims.

What I claim as new and desire to secure by Letters Patent of the United States is:

1. In a refrigeration system including a compressor, a condenser, and an evaporator, a pair of liquid receivers maintained at condenser pressure, a supply of partly miscible refrigerants in one of said receivers, a second supply of partly miscible refrigerants in separate phases in the other receiver, and means to supply at least one of said phases to said first mentioned refrigerants to vary the composition thereof.
